UNITED STATES PATENT OFFICE.

LEWIS B. DOMAN, OF ELBRIDGE, NEW YORK, ASSIGNEE TO AMPHION PIANO PLAYER COMPANY, OF ELBRIDGE, NEW YORK, A CORPORATION OF NEW YORK.

TRACKER-SHIFTING DEVICE FOR SELF-PLAYING MUSICAL INSTRUMENTS.

1,132,517.

Specification of Letters Patent. Patented Mar. 16, 1915.

Application filed April 19, 1909. Serial No. 490,796.

To all whom it may concern:

Be it known that I, LEWIS B. DOMAN, of Elbridge, in the county of Onondaga, in the State of New York, have invented new and useful Improvements in Tracker-Shifting Devices for Self-Playing Musical Instruments, of which the following, taken in connection with the accompanying drawings, is a full, clear, and exact description.

10 This invention relates to certain improvements in tracker shifting devices for self playing musical instruments involving the use of a tracker bar and perforated music sheet, and refers more particularly to manually controlled pneumatic means for shifting one of the parts laterally relatively to the other for restoring normal relation between the music sheet and tracker bar or for transposing the key one or more degrees at 15 any time before or during translation of the musical selection.

20 I am aware that tracker bars have heretofore been adjusted manually by means of a hand operated screw located in or near the plane of movement of the tracker bar, and, therefore, some distance remote from the system of manuals by which the tempo, expression and like mechanisms are controlled, such system of manuals being usually located in close proximity to the keyboard of the instrument. This screw adjustment is, therefore, not only inconvenient of access, but extremely slow of action and requires close attention to make the desired shift; as, 25 for example, in maintaining proper registration between the music sheet and tracker bar during the playing of a musical selection, thereby causing the operator to loose control of the tempo and expression controlling mechanisms while making the shift.

30 My main object is to effect the adjustment or shift of one of the relatively movable elements (preferably the tracker bar) for transposing the key or maintaining proper registration between the tracker bar and music sheet by suitable pneumatic means normally at rest under a partial vacuum and controlled by a manual or manuals located within easy reaching distance of the operator during the playing of a musical selection, as set forth in my pending application No. 461,931, filed November 1, 1908, resulting in Patent No. 939,897, Nov. 9, 1909. In other words, I have sought to effect the 35 operation of the shifting pneumatics by

varying the air tension therein through the medium of a valve located in such position that it may be operated by the finger or knee of the operator without distracting his attention from the other controlling 60 manuals.

Other objects and uses relating to specific parts of the invention will be brought out in the following description:

In the drawings—Figure 1 is a front elevation of the essential parts of my invention showing separate pneumatics at opposite ends of the tracker bar partly in section. Fig. 2 is an enlarged transverse sectional view through the atmospheric valve chamber taken on line 2—2, Fig. 1, showing the valve and its operating members, and also showing in section portions of the piano case directly in front of the key-board. Fig. 3 is a front elevation partly in section 70 of the mechanism seen in Fig. 2.

The devices shown in the drawings are particularly adapted for what is known as inside players, but the essential elements forming the subject matter of my invention 80 are clearly applicable to outside players, and for the purpose of illustrating its operation I have shown by dotted lines a perforated music sheet —1— as adapted to be moved across the face of a suitable tracker bar —2—, said tracker bar being in this instance movable endwise in opposite end supports —3—, the latter being mounted upon a supporting shelf —4—.

In Fig. 1, I have shown separate shifting pneumatics —5— and —5'— mounted in an upright position upon the shelf —4— and provided with very small bleed-holes —6— which are connected by larger conduits —7— to an exhaust conduit —8—, the latter being adapted to be connected to any suitable air exhaust device not necessary to herein illustrate or describe. The interiors of these pneumatics are connected by separate conduits —9— and —9'— to separate valve chambers —10— and —10'— which are adapted to be opened to the atmosphere but are normally closed by valves —11—. Figs. 1, 2 and 3, said valves being preferably held in their closed positions by springs —12—. These valves may be located upon any suitable portion of the piano case or other support within convenient reach of the operator while playing a musical selection, and in this instance are mounted di- 105 110 115

rectly upon a shelf —13— forming a part of the usual piano case and extended under the key-board, as —14—.

In Fig. 2 I have shown a portion of a 5 front rail —15— of the piano case as chambered out at —16— and provided with a swinging section —17— hinged at its lower edge at —18— to form when closed a continuation of the rail —15— for the purpose 10 of concealing the valve and their operating manuals, said swinging section being rocked forwardly and downwardly to the position shown when playing a musical selection to permit access to the valve operating manuals. 15

In the device shown in Figs. 1, 2 and 3 I have shown each valve —11— as provided with an upwardly projecting finger piece or manual —19— within the chamber —16—, 20 and as also provided with a pendant arm or lever —20— projecting some distance below the shelf —13— into the knee space at the under side of said shelf where it may be engaged and rocked laterally by the knee of the operator against the action of the spring —12— to open the valve, the finger pieces —19— being engaged and operated by hand for the same purpose when desired. It is evident, however, that the levers —20— may 25 be operated by hand as the operator may elect. These levers and valves, therefore, constitute what I choose to term manually operated means for controlling the action of the shifting pneumatics, the term "manual" 30 being used in its broadest sense to indicate any device actuated by the operator for opening the pneumatic to the atmosphere. One end of the tracker bar —2— is connected by a link —21— to the movable side of the 35 pneumatic —5—, while the opposite end of said tracker bar is connected by a link —21'— to the movable side of the opposite pneumatic —5'—. The pneumatics —5— and —5'— are preferably of the same size 40 or capacity, and when the tracker bar and music sheet are in normal relation, are partially distended to the same degree and retained in such partial distended position by the links —21— and —21'—. The shifting 45 pneumatics are susceptible to movement in either direction from their normal positions, and, therefore, determine the range of adjustment of the tracker bar, which is only limited by the capacity of the pneumatics. 50 The valve ports, ducts and bleed-holes communicating with the shifting pneumatics are so relatively proportioned to each other and to the capacity of the pneumatics as to cause a comparatively slow or steady action of 55 said pneumatics and tracker bar connected thereto, so as to enable the operator, through the medium of one or the other of the valves —11—, to effect any desired degree of movement of the pneumatics and tracker bar by 60 mere light pressure of the finger or knee in 65

opening the necessary valve. The endwise movement of the tracker bar is resisted more or less by its own inertia and friction in its guides, and also by the numerous tubes which are connected to its ducts, and, therefore, it requires some power—considerably more than the mere gravity of the movable sides of the pneumatics to effect such shifting movement, and it is, therefore, clear that when the pneumatic power is applied to 70 shift the tracker bar by varying the air tension in one or the other of the pneumatics, such tracker bar will remain by its own inertia and friction in its adjusted position, even after the valve —11— is closed, be- 75 cause the air tension in both pneumatics is the same and acts upon the equal areas of the movable sides thereof. The only force operating to return the tracker bar to its normal position is the mere gravity of such 80 movable side, which, however, is disposed in nearly a vertical plane and its gravity is insufficient to counteract the inertia and friction of the tracker bar. 85

It is now clear that this device as shown 90 in Figs. 1, 2, and 3 is not only positioned for convenience of manipulation without diverting the attention of the operator from the usual system of controlling levers, but that the pneumatics afford a practical and 95 highly sensitive means of adjustment whereby the tracker bar may be kept in proper registration with the music sheet or may be shifted sufficiently in either direction to transpose the key one or more degrees above 100 or below normal key. For example, assuming that it is necessary or desirable to shift the tracker bar to the left, either for restoring normal relation between the tracker bar and music sheet or for transposing the 105 key, then all that is necessary to do is to press the finger or knee against one or the other of the operating members for the left hand valve —11— to open the latter, thereby admitting atmospheric air through the 110 comparatively small duct —9— into the pneumatic —5—, and varying or increasing the air pressure in said pneumatic, while that in the opposite pneumatic —5'— is below atmospheric pressure, thus causing the 115 movable sides of both pneumatics and tracker bar connected thereto to move in the same direction to the left. The manual or physical pressure upon the valve is then released and the valve allowed to close, thereby preventing further shifting movement of the tracker bar, the pneumatics and tracker bar remaining in this position until one or the other of the valves is again opened. 120 On the other hand if it is desired or necessary to shift the tracker bar to the right, it is simply necessary to open the right hand valve —11— in the same manner as that described for the left hand valve. The 125 ducts and ports connecting the pneumatics 130

to atmosphere are comparatively small so that the inflation or distention of the pneumatics is comparatively slow but steady which enables the operator to visually follow the movement of the tracker bar relatively to the music sheet until the proper ports of the tracker bar are registered with the desired rows of perforations in the music sheet, the valve being held open by the operator until the desired shift is effected.

What I claim is—

1. In combination with a longitudinally movable tracker-bar of a self-playing musical instrument, separate pneumatics normally opposing the movement of the tracker-bar in either direction, a suction pipe connected to both pneumatics, separate atmosphere ports communicating with said pneumatics, and normally closed valves for said

ports adapted to be opened separately by an operator.

2. In combination with a longitudinally movable tracker-bar of a self-playing musical instrument, separate pneumatics normally opposing the movement of the tracker-bar in either direction, a suction pipe connected to both pneumatics, tubes communicating through relatively small bleed holes with their respective pneumatics and provided with atmosphere ports, and normally closed valves controlling said ports.

In witness whereof I have hereunto set my hand this 13th day of April 1909.

LEWIS B. DOMAN.
